DOOR CONSTRUCTION

Charles B. Malarkey, Portland, Oreg.

Application February 16, 1942, Serial No. 431,094

2 Claims. (Cl. 20—35)

This invention relates to doors, and has particular reference to a door so constructed as to resist the stresses which tend to warp the door out of a flat plane.

Doors are commonly constructed of stiles, rails and panels. The stiles and rails comprise the framework of the door, the stiles being the members which define the longitudinal edges of the door, and the rails being the cross members which unite the stiles at the top and bottom edges of the door and at intermediate points, depending upon the type of construction. The panels occupy the spaces between the stiles and rails.

In the manufacturing process, the stiles and rails are sawed and planed to the proper dimensions and delivered to the assembly room to await the operations of the workmen who fabricate the doors. After lumber is sawed it becomes subject to new stresses which tend to warp each piece out of the flat plane created by the saws. It will be appreciated that wood is not a solid homogeneous substance like steel or glass. It is made up of innumerable little hollow tubes called fibers, arranged lengthwise or along the grain in the wood. Wood fibers are added each year as the tree grows, and the size and number of the fibers added in each year's growth ring depend upon the amount of moisture, sunlight, and other plant food available to the tree during the particular year of growth. Consequently, no two pieces of lumber are exactly alike, nor is the fiber structure on one surface of a board exactly like the fiber structure on the other surface. For this reason, as moisture is absorbed by the wood fibers, the piece of lumber tends to bend into the shape which will best accommodate the moisture absorption by the fiber structure adjacent its respective surfaces. For this reason, in the manufacture of doors, for example, wherein the flatness of the door is wholly dependent upon the ability to retain the structural members in a flat plane, a great deal of difficulty is experienced due to the tendency of these members to assume a warped shape.

In the assembly room of the door manufacturing plant, only those longitudinal structural members which have remained absolutely straight are used in the fabrication of the doors. The great number of these members which have become warped are necessarily discarded. These are of clear stock, that is, free from knots, pitch seams, and the like, and represent a serious loss to the manufacturer. It has been discovered that these warped structural members can be utilized

for the purpose for which they were intended by cutting them into shorter lengths than the length of the door, and thereafter uniting in end to end relation the requisite number of pieces of door stock cut from unrelated timbers to make a stile of the required length. It is preferable that adjacent sections of the composite stile comprise a fiber structure which varies greatly in each section. In such a structure the tendency of each individual section to bend into a shape is counteracted by the tendency of adjacent sections to assume a different shape, due to the stiffening influence of panel sections which engage the inner edges of adjacent sections. This construction is particularly productive of the effect intended if the several pieces are united with the longitudinal curvature of the grain in adjacent pieces disposed toward opposite faces of the stile. In other words, adjacent sections which may be cut from a single stile are faced in the opposite direction from their original position, whereby the longitudinal center of the composite stile fabricated therefrom, instead of being warped in a long continuous curve from end to end of the stile, is caused to follow a number of pieces, in each of which the curvature is disposed toward opposite faces of the stile. Thereupon, the composite stile is run through the planer to produce the desired flat surface and a structure is had wherein the tendency to warp out of a flat plane is materially lessened.

It is the primary object of the invention to provide a door construction wherein the forces which tend to cause the door to bend in one direction are resisted by forces which tend to cause the door to bend in the opposite direction, thereby tending to hold the door in a flat plane.

A further object of the invention is to provide means for utilizing door stock which has become warped out of a flat plane for the construction of doors which are notably warp resistant.

With these and other objects and advantages in view, the invention resides in the novel construction hereinafter described and illustrated in the accompanying drawing, it being understood that various modifications of size, proportion and detail of structural features may be employed without departing from the scope of the invention.

Referring to the drawing, Figure 1 is a perspective view of a portion of a door embodying the present invention; Figure 2 is an edge view of the door illustrated in Figure 1; Figure 3 is a perspective view of a tongue and groove joint between the abutting ends of the longitudinal

structural members; Figure 4 is a section taken on the line 4-4 of Figure 1, illustrating the means for uniting the stiles and cross rails of the door; and Figure 5 is an edge view of a door illustrating a modified form of construction embodying the invention.

The drawing illustrates a door construction wherein the longitudinal structural members or stiles have been cut into a plurality of pieces of a length considerably shorter than the requisite length of the stile. Referring to Figures 1 and 2, the door stile illustrated comprises sections 1, 2 and 3 which have been joined in end to end relation by tongue and groove joints 4 to produce a composite stile of substantially uniform dimensions throughout its length. In fabricating the longitudinal structural member or stile, the pieces 1, 2 and 3 are selected to present in adjacent sections of the stile a fiber structure of greatly variant characteristics. These are so arranged that the longitudinal curvature of the grain in adjacent pieces is disposed toward opposite faces of the stile. In the construction illustrated, the longitudinal curvatures of pieces 1 and 3 are disposed in the direction of arrows 5 and 6, while the longitudinal curvature of piece 2 is disposed in the direction of the arrow 1. In this structure the forces tending to warp the door in either one of the directions indicated by the arrows are transmitted by the adjacent panel section to the adjacent stile section and thereby oppose the forces tending to warp the door in the opposite direction, with the result that the stile is held in a substantially flat plane irrespective of conditions affecting the moisture content of the wood.

The door illustrated in the drawing comprises rails 8, 9 and 10, the first and last mentioned rails constituting the top and bottom edges of the door, respectively, while rail 9 divides the space bounded by the stiles and rails 8 and 10 into panel sections 11 and 12. In the preferred construction, each of the rails 8, 9 and 10 is joined to one of the stile members 1, 2 and 3, and each of the stile members is in turn joined to one of the rails. Examination of Figure 1 of the drawing will reveal that the top rail 8 is secured to the inner edge of the stile member 1 and that the rail 9 intermediate the length of the door is secured to stile member 2, and that rail 10 is secured to stile member 3. Thus each section of the composite stile is secured to a rail, through which it is also secured to the corresponding portion of the opposite stile. Thus each section of the composite stile is supported at its ends by a tongue and groove joint by which it is joined in end to end relation with an adjacent section, and is also supported transversely of the door by a tongue and groove joint uniting it to one of the several rails of the door. Each of the stile sections 1, 2 and 3 is provided with medial grooves 13 longitudinally of the inner edge thereof for cooperatively receiving a tongue 14 on the adjacent end of the rail. This construction is clearly illustrated in Figure 4, wherein is illustrated the tongue and groove joint between the inner edge of the stile member 2 and the adjacent end of the rail 9. The medial groove 13 is aligned with the medial groove (not shown) in the inner edges of the top and bottom rails 8 and 10, and in each edge of the intermediate rail 9. The panel sections 11 and 12 engage in the medial groove of each of the opposite stiles of the door frame as well as in the medial groove in the facing edges of the rails, 75

in the well known manner illustrated in Letters Patent No. 199,871, issued January 29, 1878, to J. Springer for Manufacture of doors, etc. Thus, it will be seen that in the instant structure each panel engages the inner edges of adjacent stile sections and tends to hold them in a straight line.

The construction is productive of a door embodying the strength and rigidity inherent in doors employing stiles and rails cut from timbers of the requisite length for the door, and which also enables the fabrication of flat doors which tend to remain flat notwithstanding an unequal absorption of moisture by the wood fibers on opposite surfaces of the door.

The modification of this construction shown in Figure 5 illustrates the use of veneers 15 which comprise the surfaces of the stiles and rails. Preferably, of course, the veneers 15 are of the same species of wood as are the panels 11 and 12, so that the face of the door will present a uniform appearance. The veneers 15, being adhesively secured to the stiles and rails, add appreciably to the strength of the joints between adjacent sections of the structural members. In a door of the type illustrated the joints 4 are visible only at the edges of the door and in the moulding at the inner edges of the stile, and do not detract from the appearance of the door.

Each of the sections of the composite stile is joined in end to end relation with the adjacent sections by a tongue and groove joint made by forming the abutting ends of the several sections with interfitting tongues and grooves constructed in duplication, and yet so formed that it is necessary to turn one of the pieces side for side in order to complete the joint. This insures that corresponding surfaces of adjacent sections of the composite stile will comprise greatly differing fiber structure, and that the effect of moisture absorption thereby will vary at least in proportion to the difference in the grain structure. The end of each section of stile to be united to an adjacent section is provided with tongues 16 and 17 which define the walls of a tapering groove 18 lying therebetween into which, in the interfitting relation of the several pieces, the tongue 16 of the oppositely directed section is designed to register.

In the construction illustrated, one side of the tongue 17 is formed by the face 19 of the stile member. Adjacent the end of the tongue 17 a portion of the wood is removed to form a shoulder 20, from which point the tongue 17 is uniformly tapered to its end. Adjacent the opposite face 23 of the stile member a cut away portion 21 lying between the tongue 16 and a tongue 22 forms a groove for the reception of the oppositely directed tongue 17. The end of the tongue 22 abuts the shoulder 20 and forms a meeting face of the oppositely directed sections at the surface of the stile. An adhesive material applied to the meeting surfaces of the joints materially increases the tensile strength of the joint portion, and the joint becomes as strong as the intermediate portions of the stile.

Having now described my invention and in what manner the same may be used, what I claim as new and desire to protect by Letters Patent is:

1. A door having stiles defining the longitudinal edges of the door and rails defining the ends and intermediate cross members thereof, a medial groove in the inner edge of each said stile and in the facing edges of said rails; panel sections in said door engaging in said grooves and

extending between said stiles and rails, at least one of said stiles comprising a plurality of sections joined in end to end relation, the longitudinal curvature of the grain in adjacent sections being disposed toward opposite faces of the stile, means uniting each section of said stile with one of said rails and each of said rails with one section of said stile, each two adjacent stile sections being supported across the joint therebetween by a single panel section engaging in the medial groove of said adjacent stile sections.

2. A door having stiles defining the longitudinal edges of the door and rails defining the ends and intermediate cross members thereof, a medial groove in the inner edge of each said stile and in the facing edges of said rails, panel sections in said door engaging in said grooves and extend-

ing between said stiles and rails, at least one of said stiles comprising a plurality of sections joined in end to end relation and having corresponding faces composed of widely differing grain structure wherein in each section the tendency to warp toward one side of the door upon the absorption of moisture is counteracted by the tendency of adjacent sections to warp toward the opposite side of the door, and means uniting each section of said stile with one of said rails and each of said rails with one section of said stile, each two adjacent stile sections being supported across the joint therebetween by a single panel section engaging in the medial grooves of said adjacent stile sections.

CHARLES B. MALARKEY.
